UNITED STATES PATENT OFFICE.

SPENCER D. WRIGHT, OF PHILADELPHIA, PENNSYLVANIA.

DESIGN FOR GIMP.

40,724.

Specification for Design.

Patented June 7, 1910.

Application filed March 10, 1910. Serial No. 548,505. Term of patent 7 years.

To all whom it may concern:

Be it known that I, SPENCER D. WRIGHT, a citizen of the United States, residing at Philadelphia, in the county of Philadelphia, State of Pennsylvania, have invented a new, original, and ornamental Design for Gimp, of which the following is a specification, reference being had to the accompanying drawing, forming part thereof.

The figure is a face view of a piece of gimp showing my new design referring to which,

1 designates floats which are V-shaped in lateral direction, and 2 designates loops on the converging ends of said floats.

3 designates longitudinally extending puffs which border the floats above and below the same, and 4 designates stripes on the diverging ends of the floats joining said puffs 3.

5 and 6 designate stripes superimposed on the face proper of the gimp, they being broken and zigzagging alternately with the puffs 3, the V-shaped floats 1, and the loops 2.

I claim:

The ornamental design for gimp as shown and described.

SPENCER D. WRIGHT.
